UNITED STATES PATENT OFFICE

EDWARD OSCAR O'DELL, OF LUBBOCK, TEXAS

DOUBLE FOLDING BED

Application filed March 15, 1929. Serial No. 347,357.

This invention aims to provide an article of furniture which may be used as a side-board, a bed or a table, the construction of the device being such that it can be folded 5 up readily into small compass when not in use.

In the drawings:—Figure 1 shows the device extended to form a bed; Figure 2 is a transverse section showing the parts as they 10 will appear when the article is used as a bed; Figure 3 is a vertical section showing the device as it will appear when used as a table; Figure 4 is a section taken about on the line 4—4 of Figure 3; Figure 5 is a plan showing 15 the parts as they will appear when the device is used as a table; and Figure 6 is a sectional detail.

The device includes a body comprising a vertical back 1, sides 2 joined to the back 1 20 and provided with horizontal guides 3, and a top 4 mounted on the sides 2, a mirror 5 being carried by the top 4 at the rear edge thereof. Frames 6 are hinged at 7 for horizontal swinging movement, to the forward 25 edges of the sides 2 and include horizontal cross pieces 8 on which rest seats 9 connected to the frames 6 by longitudinally extensible interlocking pivotally mounted braces 10.

The bed includes an inner section 11 hinged 30 at 12 to an intermediate section 14, the intermediate section being hinged at 15 to an outer or foot section 16 provided at its outer end with foldable legs 17. A table 18 is hinged at 19 to the foot section 16. A brace 20 is 35 hinged at 50 to the table 18. The outer or foot section 16 of the bed has a seat 21 for the reception of the lower edge of the brace 20, under circumstances which will be pointed out hereinafter.

When the article is used as a sideboard, and neither as a bed nor as a table, the intermediate section 14 of the bed rests on the guides 3, the inner section of the bed extends 40 upwardly, parallel to the back 1, and the outer section 16 extends upwardly at the front. The table 18 is folded upwardly against the outer section 16, the brace is folded downwardly, the seats 9 are folded 45 into parallelism with the frames 6, and the frames 6 are swung backwardly into parallelism 50

relation to the sides 2. The article, therefore, occupies but small space when not in use.

When the device is used as a bed, the frames 6 are swung forwardly, the seats 9 55 are disposed as in Figure 2, the foot section 16 of the bed is swung downwardly, the bed is drawn forwardly, the inner section 11 is disposed in alinement with the sections 16, the inner section 11 is supported on the 60 guides 3, and on the inner edges of the seats 9, the intermediate section 14 is supported on the inner ends of the seats 9, the legs 17 are swung downwardly to support the outer or foot sections 16, as in Figure 1, the table 65 18 is swung upwardly against the undersurface of the foot section 16, and the brace 20 depends, to aid in holding up the foot section 16.

When the device is used as a table, the bed 70 is folded up as shown in Figure 3, the table 18 is swung downwardly and forwardly, the brace 20 is engaged in the seat 21, the frames 6 are swung forwardly, and the seats 9 are reversed, so that they extend inwardly, 75 rather than outwardly as shown in Figure 2, the seats then being located at the ends of the table, as shown in Figure 5, so that persons may occupy the seats 9 whilst the table 18 is in use.

What is claimed is:—

1. An article of furniture of the class described, comprising a body, a foldable bed carried by the body, a table hinged to the bed, means for supporting the table, frames 85 hinged to the body, and reversible seats carried by the frames, the seats being extended inwardly and being located at the ends of the table when the bed is folded and when the table is in use, and being outwardly extended, and supporting the bed, when the bed is unfolded and when the table is not in use.

2. An article of furniture of the class described, comprising a body, a foldable bed carried by the body, a table hinged to the bed, a prop for the table, when the table is in use and when the bed is folded, the prop constituting a support for the bed when the bed is unfolded and in use, side frames 95 100

hinged to the body, and reversible seats carried by the frames, the seats extending inwardly, and being located at the ends of the table, when the table is in use, and when the bed is folded, the seats supporting the bed when the bed is unfolded and when the table is not in use.

3. An article of furniture of the class described, comprising a body, a foldable bed carried by the body, a table hinged to the bed, a prop hinged to the table, and means for engaging the prop to enable the prop to hold the table in a substantially horizontal position when the bed is folded, the table being foldable to lie against the under side of the bed when the bed is unfolded, the hinged mounting of the prop enabling it to assume a substantially vertical position and serve as a floor-engaging support for both the table and the bed when the bed is unfolded and when the table lies against the under side of the bed as aforesaid.

In testimony that I claim the foregoing as my own, I have hereto affixed my signature.

EDWARD OSCAR O'DELL.
